UNITED STATES PATENT OFFICE.

CHARLES HENRY PEARDON, OF PALMYRA, WISCONSIN.

CHIMNEY-CLEANER.

1,048,868.

Specification of Letters Patent. Patented Dec. 31, 1912.

Application filed May 29, 1911. Serial No. 630,071.

To all whom it may concern:

Be it known that I, CHARLES H. PEARDON, a citizen of the United States, residing at Palmyra, in the county of Jefferson and 5 State of Wisconsin, have invented a new and useful Chimney-Cleaner, of which the following is a specification.

This invention relates to chimney cleaning devices, its object being to provide a 10 simple and effective cleaner that may have either a handle or a rope and weight attached thereto for operating it.

With the foregoing and other objects in view which will appear as the description 15 proceeds, the invention resides in the combination and arrangement of parts and in the details of construction hereinafter described and claimed, it being understood that changes in the precise embodiment of 20 the invention herein disclosed can be made within the scope of what is claimed without departing from the spirit of the invention.

In the accompanying drawings the preferred form of the invention has been 25 shown.

In said drawings: Figure 1 is a side elevation of the cleaner with a handle attached to it. Fig. 2 is an end elevation of the cleaner with the screw eye removed. Fig. 3 30 is a detail view of the handle-attaching screw. Fig. 4 is a detail view of a screw eye which may be used for connecting a cable or rope to the block of the cleaner. Fig. 5 is a section on line A—B of Fig. 1.

35 Referring to the figures by characters of reference 1 designates a block preferably of wood and rectangular, and secured to one face of this block, as by means of fastenings *a*, is a scraper preferably formed of four 40 plates 3', the ends of which are cut diagonally so as to fit together snugly. The outer edge portions of these plates project beyond the margin of the block.

Bristles are secured to and extend from 45 the marginal portion of the block 1 and project short distances beyond the outer edges of the plates 3'.

As shown particularly in Figs. 1 and 5,

these bristles are spaced from the scraper plates so as thus to be free to flex toward the 50 plates.

A screw 5 normally extends into the center of the block 1 at one side and has a disk like head 6 secured in any suitable manner to one end of a handle 4. Thus it will be 55 seen that, by means of this handle, the cleaner can be moved upwardly and downwardly within a chimney so as to bring the scraping plates 3' into engagement with the walls and also to bring the bristles into contact with them. The scraping plates will 60 dislodge incrustations from the walls, while the bristles will brush the soot, etc., from the chimney.

The screw eye 8 extends into the center of 65 the block 1 directly opposite the screw 5 and, should it be desired to employ a rope and weight, instead of the handle 4, for actuating the cleaner, a suitable weight, not shown, may be attached to the eye 8 while a screw 70 eye 7, such as shown in Fig. 4 may be substituted for the screw 5 and handle 4. A rope can then be attached to the screw eye 7 and by this means the weighted cleaner can 75 be lowered into a chimney and then pulled upwardly so as thus to thoroughly clean the walls of the chimney.

What is claimed is:—

A chimney cleaner, composed of a rectangular block forming the main body of the 80 cleaner, brush bristles secured to and projecting from four sides of the block, and a sheet metal scraper composed of four sections, each of the sections being secured upon the face of the block and having its 85 free edge disposed beyond the sides of the block and terminating within and parallel to the outer ends of the bristles.

In testimony that I claim the foregoing as my own, I have hereto affixed my signature 90 in the presence of two witnesses.

CHARLES HENRY PEARDON.
